HARRY W. DENHARD, OF SAN FRANCISCO, CALIFORNIA, ASSIGNOR TO THE CUTLER-HAMMER MFG. CO., OF MILWAUKEE, WISCONSIN, A CORPORATION OF WISCONSIN.

ELECTRIC RESISTANCE ELEMENT.

1,143,574.

Specification of Letters Patent. Patented June 15, 1915.

Application filed October 31, 1911. Serial No. 657,802.

To all whom it may concern:

Be it known that I, HARRY W. DENHARD, a citizen of the United States, residing at San Francisco, in the county of San Francisco and State of California, have invented new and useful Improvements in Electric Resistance Elements, of which the following is a full, clear, concise, and exact description, reference being had to the accompanying drawing, forming a part of this specification.

My invention relates to electric resistance elements.

It is especially adapted for use in connection with electric heating devices, such as electric laundry irons, and it is in this connection that I shall describe the same in this application. My invention is not however, limited in its use to this specific adaptation.

My invention has among its objects to provide an improved electric resistance element which may be manufactured at very small expense and assembled in a very compact form, so that the heat generated by the same is distributed in proper proportion to the object to be heated.

A further object of my invention is to provide an improved electric resistance element adapted to use in connection with an electric iron, which is formed of a plurality of strips of resistance material which are so made as to permit them to be assembled in the form of a unit which conforms to the shape of an iron and which distributes the heat generated in the desired proportion to the various parts of the iron.

Other objects and advantages of my improved construction will hereinafter appear.

In the accompanying drawings I have illustrated one form which my invention may assume in practice. My invention is not however, limited to this specific form.

In the view of these drawings:—Figure 1 shows a plan view of a blank from which the resistance element is formed. Fig. 2 shows a plan view of an assembled unit. Fig. 3 shows a sectional view of the unit in position in an iron.

In the construction shown in the drawings, a blank 1, of a resistance material, preferably metallic, is made up in the form of a strip and punched as illustrated in Fig. 1. This blank is preferably slotted throughout the greater part of its length as at 2, (Fig.

1) in the well known manner and one side 55 of the same is tapered toward a point near the middle 3, which when the blank is bent into the shape of a unit, forms the tip of the same. In order that the heat may be greater at the tip of the iron, due to the fact 60 that the heat is more readily dissipated at the tip, I so arrange the unit that a greater heat developing surface is present at the tip. This I do by bending the blank along a horizontal line at the point 3, until the two 65 halves of the same lie in horizontal planes. Since it is unnecessary to heat the back of the iron, to the high temperature required at the tip, I preferably leave one end of the blank unslotted, as shown at the lower part 70 of Fig. 1. In order to enable the unit to be held in position in the iron, I preferably provide suitable perforations 4, which when the unit is assembled, are arranged concentrically. In order to enable suitable electric connections to be made, I provide each of the blanks with an extension 5, at one of its ends, which is preferably stamped out with the blank, and I also preferably provide a perforation 6, at the opposite end, so 80 that the terminals may be connected to the unit as by riveting if desired.

When the unit is assembled it assumes the form shown in Fig. 2, wherein the two halves of the blank shown in Fig. 1 are folded upon each other along the line 3, so that when the two halves are placed together with their straight edges in parallel relation, a unit is formed which will conform to the shape of an iron, in which it is desired to place 90 the same. When in this position, the lower flap of the blank shown in Fig. 1 rests upon the flap shown at the top, and the perforations 4, register with each other, while the perforations 6 are brought close together 95 at the back of the iron. The extensions 5, at the back of the units, are connected together in any suitable manner as by crimping or if desired, by brazing or welding, so that a complete unitary structure is provided. In 100 order to insulate the parts, the two flaps which are bent over upon each other may be suitably spaced from each other by a sheet of insulation 7. If desired I may use mica as this insulation.

In Fig. 3, I have shown one manner in which the unit may be placed in position in an iron. For purposes of illustration, the

parts of the unit have been shown considerably enlarged. In actual practice, the unit will be very thin, and the space between the parts of the iron will be very much less than that shown. Before the unit is placed in position in the iron, it is placed between sheets of insulation 8. In preferred form, I employ mica as this insulation. When placed between these sheets of insulation 10 the unit is then placed between the storage plate 9, and the body portion 10, of the iron, as shown in Fig. 3. As usual in such constructions, the plate 9 may be brought down very tightly upon the unit by means of 15 suitable screws, or bolts 11 so that the unit is clamped between the surface of the plate and the body portion of the iron. Since this form of clamping the unit within the iron is well known, I have not illustrated the 20 same in detail in the drawing.

By my improved construction, I am able to produce a unit which may be made up into very thin form, so that it may be brought into intimate relation with the surface 25 face to be heated, and thus reduce the amount of heat lost through radiation or otherwise. Further, by the use of the slotted resistance material, I am able to provide a unit of high heating capacity. By my improved means of arranging the unit, I am able to distribute the heat to the parts of the iron where it is most needed, and in the desired proportion, so that a practically uniform temperature may be maintained. 30 Further, I am able to provide an efficient unit of high heat developing capacity which may be manufactured very cheaply and be readily placed in position.

While I have, in this application, described one form which my invention may assume in practice, my invention may assume other forms than that shown, and I accordingly wish to cover within the scope of this application all of these forms of my 45 invention falling within its spirit.

What I claim as new and desire to secure by Letters Patent is:—

1. An electric resistance unit formed of a pair of strips of slotted resistance ribbon 50 each bent back on itself to form parallel portions, said portions being of similar shape and conforming to the outline of the object to be heated, the lower portion having slots throughout its length and the upper portion having slots for a portion of its length whereby the maximum quantity of heat is developed at one end of the unit, the

other end of said unit being adapted to be connected to the electric terminals.

2. An electric heating unit for irons having two strips of slotted resistance ribbon, each bent back on itself to form parallel portions, insulating means between the portions, said portions being of similar shape and of an area substantially equal to half the area of the base of the iron, the lower portions of each strip being connected together electrically at their free ends and slotted throughout their length, the upper portions of each strip being slotted near the bent-over end whereby the maximum quantity of heat is generated at one end of the unit, the free end of the upper portions of the strips being adapted to be connected to electric terminals. 75

3. An electric heating unit having a pair of strips of slotted resistance ribbon adapted to conform to the outline of the object to be heated and each having an area substantially equal to the area of one-half of the base of said object, each of said strips having a terminal portion which is bent back on the strip and insulated therefrom, said terminal portions being slotted adjacent their bent-over ends whereby the unit has a maximum heat developing capacity near one end, the free ends of said terminal portions being adapted to be connected to an electric circuit. 85

4. An electric resistance unit formed of a single length of slotted resistance ribbon having a body portion and a partially slotted terminal portion bent over upon one surface of the body portion and insulated therefrom, whereby the unit has a maximum heat developing capacity near one end, the outline of said terminal portion being shaped to coincide with the outline of said body portion and both conforming to the shape of the surface to be heated. 95

5. An electric resistance unit formed of a single length of slotted resistance ribbon having one edge of the same tapered toward the center of the strip, said strip being folded substantially at its middle line to form two layers, the end of one of said layers being left unslotted. 100

In witness whereof, I have hereunto subscribed my name in the presence of two witnesses.

HARRY W. DENHARD.
